CLAIM

The ornamental design of a simulative picture frame, as shown and described.

DESCRIPTION

FIG. 1 is a top plan view of a simulative picture frame showing my new design;

FIG. 2 is a front elevational view thereof;

FIG. 3 is a bottom plan view thereof;

FIG. 4 is a side elevational view thereof, the side opposite this side being a mirror image of this figure;

FIG. 5 is a rear elevational view thereof; and,

FIG. 6 is a front elevational view of the picture frame shown omitting the base for ease of illustration.
